*Primary Examiner—Alan P. Douglas**Assistant Examiner—Caron D. Veynar***[57]****CLAIM**

The ornamental design for a checkbook calculator, as shown and described.

DESCRIPTION

FIG. 1 is a front, top and left perspective view of a checkbook calculator showing my new design; the broken line showing of a checkbook is environmental only and forms no part of the claimed design;
FIG. 2 is a front elevational view thereof;
FIG. 3 is rear elevational view thereof;
FIG. 4 is a top plan view thereof;
FIG. 5 is a bottom plan view thereof;
FIG. 6 is a right elevational view thereof; and,
FIG. 7 is a left elevational view thereof.
